Inventor,

William J. Black

UNITED STATES PATENT OFFICE.

WILLIAM JACKSON BLACK, OF ALVORD, TEXAS, ASSIGNOR OF TWO-THIRDS
TO JOHN BEYETT AND C. K. THOMAS, OF SAME PLACE.

WHIFFLETREE.

SPECIFICATION forming part of Letters Patent No. 403,904, dated May 28, 1889.

Application filed May 5, 1888. Serial No. 272,919. (No model.)

To all whom it may concern:

Be it known that I, WILLIAM JACKSON BLACK, a citizen of the United States, residing at Alvord, in the county of Wise and State of Texas, 5 have invented new and useful Improvements in Whiffletrees, of which the following is a specification.

The invention relates to improvements in whiffletrees.

10 The object of the invention is to improve the construction of whiffletrees and render them more efficient and durable, and to diminish the cost of their construction.

15 The invention consists in the novel construction and arrangement of the parts, hereinafter fully described, illustrated in the accompanying drawings, and pointed out in the claim hereto appended.

20 In the accompanying drawings, forming part of this specification, and in which like letters of reference designate corresponding parts, Figure 1 is a perspective view of a whiffletree designed to be attached to a wagon. Fig. 2 is a transverse sectional view of Fig. 1. 25 Fig. 3 is a plan view of the whiffletree, the top of the casing being removed to expose the strengthening-piece of metal; Fig. 4 is a detail plan view of an end of a whiffletree, illustrating the manner in which the ends are 30 bent over and welded together to construct a loop.

Referring to the accompanying drawings, A designates a whiffletree consisting of a front bar, a, and a back rod or spring, a', made of 35 suitable material, preferably malleable iron. The ends of the front bar, a, and the back rod or spring, a', meet at an angle and are welded together, making the front bar and the back rod or spring practically integral with each 40 other. At the ends of the whiffletree are formed eyes or openings a², in which are secured suitable devices for attaching the traces or singletrees. As most clearly illustrated in Fig. 4 of the drawings, the ends of the front 45 bar and the back rod or spring are welded together and bent back to construct the eye or opening a², and then the parts are again welded together to preserve the construction, thereby passing both the bar and rod around 50 the eye or opening.

In order to strengthen the whiffletrees and render them strong and durable, a strengthening-piece of metal, B, of a thickness a little less than the diameter of the front bar, a, is placed between the front bar and the back rod or spring and intermediate of the ends of the whiffletree A. The sides of the strengthening-piece of metal, B, conform to the configuration of the front bar, a, and the back rod or spring, a'—that is, its front edge is straight and its back edge is slightly apexiform; and it is secured in place by a casing, C, made of suitable material, such as sheet-iron or brass.

The casing C is of the same size and shape as the strengthening-piece of metal, B, and it 65 consists of two sides or plates, d and d', one of which is on one side of the strengthening-piece B, and the other on the other side; and they are connected together by integral straps, d², located at the rear of the casing and on 70 each side. The sides d and d' of the casing C are secured to the strengthening-piece B by rivets D. At the front of the whiffletree A the casing extends out beyond the strengthening-piece B and rests on the front bar, a, 75 thereby forming, with the outer edge of the strengthening-piece B, a groove, d³.

In the center of the casing C is a hole, E, passing through the strengthening-piece B and the sides of the casing C, and adapted 80 for the reception of a pin to connect the whiffletree to the draft-bar of a plow or the tongue of a wagon or carriage, or the like, or in case of a singletree for a suitable device to connect to the end of a doubletree. By this construction the draft is thrown upon the back rod or spring, leaving the front bar loose in the groove d³.

The whiffletrees are increased in thickness or bulged out on their under sides around the 90 hole E, whereby the main body of the whiffletree is raised up and enabled to swing clear of the supporting-surface.

From the foregoing description and the accompanying drawings, the construction, operation, and advantages of the invention will 95 readily be understood.

Of course I would have it understood that I do not limit myself to the precise details of construction herein shown and described, and 100

I may, without departing from the spirit of my invention, make any minor changes therein; and I also propose to construct neck-yokes in accordance with this invention.

5 Having thus fully described my invention, what I claim as new, and desire to secure by Letters Patent, is—

A whiffletree comprising a front bar, a back rod or spring united to the front bar by welding, the ends of both said bar and rod being bent upon themselves and the parts welded together to construct an eye or opening, whereby both bar and rod are bent around

the latter, substantially as shown in Fig. 4, a strengthening-piece placed between the front bar and the back rod or spring, and a casing secured to the back rod and adapted to hold the strengthening-piece in place, substantially as described.

In testimony that I claim the foregoing as my own I have hereto affixed my signature in presence of two witnesses.

WILLIAM JACKSON BLACK.
